[57] CLAIM

The ornamental design for a hinge, as shown and described.

DESCRIPTION

FIG. 1 is a perspective view of a hinge embodying our new design;

FIG. 2 is a side elevational view thereof, the opposite side being the mirror image thereof;

FIG. 3 is a front elevational view thereof;

FIG. 4 is a rear elevational view thereof;

FIG. 5 is a top plan view thereof;

FIG. 6 is a bottom plan view thereof;

FIGS. 3-6 are shown on an enlarged scale in comparison to FIGS. 1 and 7-8.

FIG. 7 is a perspective view similar to FIG. 1 but with the two hinge elements separated from one another; and,

FIG. 8 is a perspective view of the hinge in a different position.
